UNITED STATES PATENT OFFICE.

EDGAR L. YORK, OF PEORIA, ILLINOIS, ASSIGNOR TO OASIS MANUFACTURING CO., OF PEORIA, ILLINOIS, A CORPORATION.

IRONING MACHINE.

Application filed April 19, 1920. Serial No. 374,832.

To all whom it may concern:

Be it known that I, EDGAR L. YORK, a citizen of the United States, and a resident of Peoria, in the county of Peoria and State of Illinois, have invented certain new and useful Improvements in Ironing Machines, of which the following is a full, clear, and exact description, reference being had to the accompanying drawing, forming part of this specification.

My invention relates to machines primarily intended for family use and which comprise a rotating cylinder against which an ironing element is held, the clothes or other articles to be ironed passing between the cylinder and ironing element.

One object of my invention is the provision of disengageable and reversible driving mechanism for the cylinder of the machine.

Another object of my invention is the provision of means whereby the ironing element may be held in proper relation to the cylinder, and the provision of means whereby the ironing element may be moved a considerable distance from the cylinder so that the operating face of the ironing element may be reached for cleaning or waxing, as desired.

Another object of my invention is the provision of an attachment to the machine whereby collars or other articles may be ironed, the attachment being so mounted and arranged that it may be driven from the driving mechanism of the machine and may be employed to iron articles which, owing to their shape may not be satisfactorily ironed by the main ironing cylinder and its ironing element.

Another object of my invention is the provision of a spraying device for sprinkling the goods to be ironed before the ironing operation.

Other objects of my invention will appear and be described in the specification.

The novelty of my invention will be hereinafter more fully described and specifically pointed out in the claims.

In the accompanying drawings:

Fig. 1 Sheet 1 is an end elevation of a machine embodying my invention.

Fig. 2 Sheet 1 is a rear elevation of the right end of the machine.

Fig. 3 Sheet 1 is an enlarged view of the ironing element supporting mechanism.

Fig. 4 Sheet 1 is a detail view of a portion of one of the pedals of the machine showing its latch.

Fig. 5 Sheet 2 is a plan view, partly in section, of the driving connections for the machine.

Fig. 6 Sheet 2 is a sectional end elevation taken on the dotted line 6—6 of Fig. 5, this view being turned to its true position as shown in Figs. 1 and 2.

Fig. 7 Sheet 2 is a view corresponding to Fig. 6 but taken on the line 7—7 of Fig. 5, the driving pulley and some of the other parts being omitted.

Fig. 8 Sheet 2 is an enlarged end view of the driving mechanism for the spraying device, the view being taken on a plane approximately coinciding with the inner face of the driving pulley of the machine.

Fig. 9 Sheet 2 is an enlarged detail of the disengageable tension device for the auxiliary iron attachment.

The same characters of reference are used to indicate identical parts in all the figures.

In its preferred form of construction my machine comprises end members 1 which form the legs for supporting the machine and to which the various other parts of the machine are attached, the end members being connected by a work table 2, a work receiving apron 3, and brace rods 4 and 5 thus forming a substantial frame.

The ironing cylinder 6 is provided with a trunnion 7 at each end and these trunnions have their bearings in the members 1, and that trunnion which has its bearing in the right member 1, when viewed from the front is provided with a worm-wheel 8, the worm-wheel 8 and trunnion 7 and cylinder 6 being shown in dotted lines in Fig. 1.

A gear case 9 is mounted on the member 1 and by referring to Fig. 5 it will be seen that this gear case contains a worm 10 which meshes with the worm-wheel 8, and is mounted on a shaft 11, the shaft being journaled in the gear case 9 and preferably provided with ring oilers 12. A pair of duplicate bevel gears 13 are mounted free to turn on the shaft 11 and each carries a series of clutch jaws 14 which are adapted to be engaged by jaws 15 carried by a spool 16 which is feather keyed as at 17 to the shaft 11, the spool 16 being adapted to be shifted so that its clutch jaws engage the clutch jaws of one or the other of the gears 13, the shifting

mechanism comprising a crank arm 18 carried on a shaft which is journaled in the boss 19 of the gear case 9, a crank arm 20 being also mounted upon this shaft to the 5 end that the operation of the crank arm 20 will shift the spool 16, the crank arm 18 being better shown in Fig. 7.

A driving pinion 21 meshes with both of the gears 13 and is mounted upon a shaft 22 10 which also carries the driving pulley 23, the shaft 22 being journaled in a bracket 24 which is suitably attached to the gear case 9.

Referring again to Figs. 1 and 2 the pulley 23 is protected by a guard 25 which extends to a motor 26 and encloses the driving belt from the motor to the driving pulley 23.

A bracket 27 is mounted upon the end member 1 and carries small ironing cylinder 28 above which an ironing element 29 is mounted as by the arm 30 which is provided with a handle 310 so that the ironing element 29 may be raised or lowered by the operator. The arm 30 is pivotally mounted 25 as at 31 on the bracket 27 and is provided with a tension device which comprises a spring 32 which bears against a bifurcated lug 33 and surrounding an eye bolt 34 which is pivotally connected to a lug 35 of the bracket 27 and is provided with a wing nut 36, which as shown more clearly in Fig. 9 is provided with a collar 37 which is of greater length than the thickness of the lug 23 and bears against a washer 38 above the spring 35 32 to the end that the spring 32 may be compressed to relieve its tension from the arm 30 whereupon the eye bolt 34 may be swung rearwardly to disengage the lug 33 so that the arm 30 and the ironing element 29 may 40 be raised substantially to a vertical position.

The bracket 27 carries a gear case 39 within which a bevel gear 40 is mounted, the gear 40 driving the cylinder 28 and being driven by a pinion 41 which is carried on 45 the vertical shaft 42, this shaft being shown in section in Fig. 5 and a portion of it in elevation in Fig. 6.

The shaft 42 carries a splined worm wheel 43 which engages a worm 44 on the shaft 11 50 but which may be disengaged therefrom by being raised until the pin 45 (Fig. 6) passes through the slot 46 of the cover of the gear case whereupon the worm wheel 43 may be turned to bring the pin 45 in contact with 55 the cover of the gear case thus disengaging the worm wheel 43 from the worm 44, a spring 47 being mounted upon the shaft 42 and bearing against the upper end of the hub of the worm wheel 43 and a collar 48 60 (Figs. 1 and 2) on the shaft 42, the construction being such that when it is desired to re-engage the driving connections for the shaft 42, it is only necessary to turn the worm wheel 43 until its pin 45 comes to the slot 46 65 whereupon the spring 47 will cause and

maintain the engagement between the worm wheel and the worm.

Referring to Figs. 5 and 8 an eccentric 49 is mounted free to turn upon the bracket 24 and held in place by a collar 50, the eccentric 49 being provided with a driving lug 51 which is adapted to be engaged by a key 52 mounted between a pair of guides 53 carried within the cone shaped portion of the driving pulley 23 and operated by a button 54 which extends to the outside of the cone, the construction and operation of these parts being such that when the key 52 is in the position shown in Fig. 5 it will engage the lug 51 of the eccentric 49 thereby turning 80 ameter of the cone portion of the pulley 23, turned, and that when the key 52 is moved between the guides 53 toward the small diameter of the cone portion of the pulley 23, it will release the lug 51 of the eccentric 49 85 so that the driving pulley 23 may be turned without engaging the eccentric 49.

The eccentric 49 operates an eccentric rod 55 which is connected to the cross head 56 of an air pump 57 (Fig. 5), the discharge 90 from the air pump as shown in Fig. 1 being conducted through hose 58 to an atomizer 59, the atomizer being provided with a suction hose 60 which is adapted to be placed in a bucket of water so that when the valve 61 of the atomizer 59 is operated, the air passing through the nozzle of the device will raise the water from the bucket and spray it upon the clothes.

The machine is preferably provided with 100 two pedals 62 and 63, the pedal 62 being attached to the square brace rod 5, at a point intermediate its ends, the rod 5 carrying a crank arm 64 adjacent each of the end members 1. Each of the crank arms has a 105 connecting rod 65 attached thereto, the connecting rod 65 extending to and being connected with the bell crank 66 which is pivotally mounted as at 67 (Fig. 1) upon the end member 1 and operates a rod 68 which is provided with an adjusting nut 69 which rests against the lower portion 70 of a bell crank 71, this bell crank and the parts to which it is connected being more 110 clearly shown in Fig. 3. The lower portion 70 of the bell crank 71 forms a pocket within which a portion of the compression spring 72 is mounted, the spring 72 bearing against the end member 1, its tension being exerted to force the lower portion of the bell crank 71 away from the end member 1.

The upper portion of the bell crank 71 is beveled as shown at 73 and is engaged by a latch 74 which is pivotally mounted as at 75 upon the supporting arm 76, this arm 125 being pivotally mounted as at 77 on the axis of movement of the bell crank 71, the upper end of the arm 76 engaging a trunnion 78 carried by the ironing element 79 which, when the parts are in the position 130

shown in Fig. 3, rests against the cylinder 6, being held in contact therewith by the tension of the spring 72 through the medium of the latch and mountings previously described.

It frequently happens that it is necessary to release the ironing element from its contact with the cylinder 6 and this is accomplished by pressing upon the pedal 62 which 10 rocks the rod 5 and compresses the spring 72 to move the ironing element away from the cylinder through the medium of the rod 68, bell crank 66 and connecting rod 65 previously described.

15 The pedal 62 carries a lug 80 shown more clearly in Fig. 4, and which is engaged by a latch member 81 which is mounted free to turn on the rod 4, the latch member being shaped as shown in Figs. 1 and 4 and being 20 provided with a detent 82 which is adapted to engage the lug 80 when the pedal 62 reaches the dotted position 83 thus compressing the spring 72 moving the ironing element 79 away from the cylinder 6 and 25 latching it in this position.

To release the latch 81 the pedal 62 is quickly depressed from the dotted position 83 to the dotted position 84 whereupon the lug 80 throws the latch 81 to the dotted 30 position 85 and permits the pedal 62 to be quickly raised to a position just above the detent 82 whereupon it may be further raised until the ironing element has again resumed the position shown in Fig. 3.

35 The movement produced in the ironing element by the connections just described is only sufficient to freely release the material which is being passed through the machine, so that the material may be drawn back or 40 so that a portion of it may be passed through the machine without being ironed.

To move the ironing element from the position shown in full lines in Fig. 3 to the position shown in dotted lines, the pedal 62 45 is depressed and the latch 81 engaged thus slightly compressing the spring 72 and removing its tension from the ironing element whereupon the latch 74 may be operated, there being one of these latches at each end 50 of the machine, the latches being connected together for simultaneous operation by the rod 86 of Fig. 2 which is connected to the free ends of the latches and forms a handle for their simultaneous operation, whereupon 55 when the latches 74 have been disengaged from the upper end of the bell cranks 71, the arms 76 may be swung upon their pivot 77, each of the arms 76 carrying a quadrant 87 which acts as a movement limit by coming in contact with the bell crank 71 when 60 the arms 76 and the parts which they carry reach the dotted position shown in Fig. 3.

Each arm 76 carries a trunnion 88 which 65 engages a recess 89 in the end of the ironing element 79, the recess 89 being larger

than the trunnion 88 to the end that the ironing element has a restricted pivotal movement on its trunnions 78 so that it will properly conform in position to the surface of the cylinder 6 even though that surface 70 may be slightly eccentric or the material passing through the machine be of variable thickness, the function accomplished by this portion of the structure being to prevent a localization of the pressure of the ironing element upon any inequality of the surface of the cylinder 6.

It is to be noted that when the ironing element is in the dotted position shown in Fig. 3, it has been moved sufficient distance 80 to permit the operator to clean its ironing surface if desired.

The ironing element may be restored to its operative position by grasping the rod 86 and raising it and the parts to which it 85 is connected to bring the latches 74 into engagement with the upper ends of the bell cranks 71 whereupon the pedal 62 may be operated as previously described to release the latch 81 thus restoring the ironing element to its contact with the cylinder 6.

Each of the latches 74 carries a spring pocket 90 in which a spring 91 is mounted, the spring bearing against a lug 92 which is carried by the arm 76 this lug being 95 notched to engage a portion of the upper end of the bell crank 71 to stiffen the structure and prevent endwise displacement of the ironing element 79, it being noted that the upper end of each bell crank 71 rests in 100 the notch of the lug 92 when the latch 74 is engaged with the upper end of the bell crank so that movement in either direction of the bell crank 71 on its pivot is imparted to the arm 76.

105 It is to be noted that each of the ironing elements 79 and 29 are intended to be heated either by steam, gas, electricity, or other suitable means and as a means of making the proper connections I have shown an 110 opening 92 through the end of the ironing element 79 and an opening 93 in the rear wall of the ironing element 29.

The pedal 63 is mounted free to turn upon the rod 5 and is connected, through the rod 115 94 with the crank arm 20, a compression spring 95, Figs. 1 and 2 bearing against a collar 96 on the rod 94 and against a lug 97 carried by the end member 1 to the end that the rod 94 will be held in its uppermost position to cause the engagement of the jaws of the spool 16 of Fig. 5 with the forward driving gear 18, it being apparent that by depressing the pedal 63 the spool 16 is shifted to engage the driving jaws of the rearward driving gear 13 previously described.

120 A latch similar to the latch 81 or a pin 98 may be employed to engage the pedal 63 to hold it in a position which will shift the spool 16 to a neutral position between the 125 130

two driving gears 13 to stop the operation of the shaft 11 and the parts which it drives, the pedal 63 being sufficiently loosely mounted so that when depressed, it may be shifted sidewise to come under the pin 98.

When it is desired to operate the atomizer 59, the pedal 63 may be moved to and latched in its neutral position and the button 54 moved to operate the key 52 to engage the lug 51 of the eccentric 49, and the motor 26 set in motion whereupon none of the parts of the machine with the exception of the air pump 57 will be operated.

After the clothes have been sprinkled the 15 motor is stopped and the button 54 moved in the reverse direction to disengage the eccentric 49 and the heating device in either or both of the ironing elements 79 and 29 is brought into action to heat these elements.

20 When the proper temperature has been obtained, the motor is again started and the pedal 63 moved to the forward driving position as shown in Fig. 1 whereupon the clothes are passed through the machine and ironed.

If desired the ironing element 79 may be used and the ironing element 29 not heated until time to iron those garments which are ironed on the cylinder 28 and during the 30 operation of the cylinder 6, the worm wheel 43 may be disengaged from the worm 44 as previously described and all the power of the machine utilized for driving the cylinder 6.

35 After the completion of the operations in connection with the cylinder 6, the ironing element 29 may be heated, the ironing element 79 may be disengaged by the operation of the pedal 62 and its supply of heat 40 cut off, whereupon the worm wheel 43 is engaged with the worm 44 the operator taking his position adjacent the right end of the machine and those garments which are to be ironed by the element 29 45 passed through this portion of the machine, the operator by resting one foot on the pedal 63 operating the cylinder 28 in either direction at will by either pressing or releasing the pedal 63 as previously described.

50 In the ironing of collars, owing to their several thicknesses and especially those collars which are turned or folded over, greater speed of operation may be obtained 55 by passing the collar back and forth under the ironing element 29 by reversing the machine. To properly finish the folded edge of the collar, a grooved portion 99 (Fig. 1) is provided on the forward face 60 of the ironing element 29 and the collar may be passed through this portion to properly round and smooth its edge.

65 During the time that the ironing elements are being heated, and at intervals during the operation of the machine, it is

advisable that the ironing elements be held from contact with the cylinders, and to that end the pedal 62 may be latched in its lower position thereby holding the ironing element 79 away from the cylinder 6. To accomplish the same result in connection with the ironing element 29, it will be noted that the arm 30 is provided with a comparatively large bore in its lower end, as shown more clearly in Fig. 9; and an eccentric 100 is mounted within this bore and is provided with an operating handle 101 which extends upwardly as shown in Figs. 1. and 2., this handle being engaged by a blade spring 102, which is carried by the arm 30, the pivot 31 previously described passing through the eccentric 100. The construction and operation of the parts just described is such that when it is desired to raise the ironing element 29 from contact with the cylinder 28, the handle 101 is moved rearwardly and downwardly, thereby partially rotating the eccentric 100 and thereby raising the lower end of the arm 30 and bringing the upper face of the bifurcated lug 33 into contact with the flange of the wing-nut 36 and raising the ironing element 29 from contact with the cylinder 28.

When the tension device for the arm 30 has been released so that this arm may be raised as previously described, to approximately vertical position the handle 101 moves with the arm 30, the blade spring 102 serving as a means to normally maintain these parts in the position shown in Figs 1. and 2. with relation to each other.

Having thus fully described my invention, I claim:

1. In an ironing machine the combination of a work carrying surface, an ironing element cooperating with said surface, yielding means for holding the ironing element against said surface, means for overcoming the yielding holding means to release the ironing element from contact with said surface, and means for disengaging the ironing element from the operation of the yielding holding means whereby the ironing element may be moved a relatively great distance from the work carrying surface.

2. In an ironing machine the combination of a cylinder, an ironing element cooperating therewith, driving connections for the cylinder, pivotally mounted supporting arms for the ironing element, operating arms cooperating with the supporting arms, and a latch carried by one of the arms whereby when the latch is engaged the arms will operate together and when the latch is disengaged the supporting arms and the ironing element may be moved a considerable distance from the cylinder.

EDGAR L. YORK.
